CLAIM

I claim the ornamental design for a wheel for motor vehicle, as shown and described.

DESCRIPTION

FIG. 1 is a perspective view of a wheel for motor vehicle, showing my design;

FIG. 2 is a front view thereof; and,

FIG. 3 is a side view thereof.

The additional views of the wheel not provided herein do not provide any additional claimed features of the design and thus are not represented. The broken lines are included for illustrating environmental structure and form no part of the claimed design.
